CLAIM

The ornamental design for a physical exerciser, as shown and described.

DESCRIPTION

FIG. 1 is a top plan view of a physical exerciser showing our new design;

FIG. 2 is a bottom plan view thereof;

FIG. 3 is a left side elevational view thereof, the right side elevational view thereof being a mirror image of the left side elevational view; and,

FIG. 4 is a front elevational view thereof, the rear elevational view being identical to the front elevational view.
